FROTH FLOTATION CELL

Donald S. Phelps, Harvard, Mass.

Application May 19, 1944, Serial No. 536,230

3 Claims. (Cl. 209—168)

1

This invention relates to froth flotation apparatus, and more particularly to improving the aeration and separation of values from pulp.

It is an object of the invention to improve the aeration of pulp by causing pulp to be discharged in the open air and directed against a body of pulp at a relatively high velocity whereby air is entrained and froth is produced.

Another object of the invention is to provide a frothing cell capable of subjecting all of its contained pulp to circulation and aeration so that the material not entrained in the froth is afforded recurring opportunity to be directed to the froth and recovered as concentrate. This results in the thorough mixing of air and pulp and recovery of coarse particles which otherwise would be lost.

Another object of the invention is to provide a frothing cell wherein a froth forming portion is localized in symmetrical relation to the froth-overflow lip of the cell and the cell functions automatically to direct the generated froth outwardly towards the overflow lip of the cell as it rises through the pulp.

A still further object of the invention is to provide cells or flotation machines which are capable of group operation in a battery having any desired number of units efficiently operable on a single floor level.

Further and other objects of the present invention will be hereinafter set forth in the accompanying specification and claims and demonstrated by the drawings which show by way of illustration a preferred embodiment and the principle of my invention and what I now consider the best mode in which I have contemplated applying that principle. Other embodiments of the invention employing the same principle may be used and structural changes made as desired by those skilled in the art within the spirit of the appended claims and without departing from the present invention.

In the drawings,

Fig. 1 illustrates a vertical section of a unit employing my invention.

Fig. 2 is a plan of the unit illustrated in Fig. 1.

Fig. 3 is a section on line 3—3 of Fig. 2.

Fig. 4 is a section on line 4—4 of Fig. 1.

Fig. 5 is a vertical section of a modified form of unit.

Fig. 6 shows a schematic arrangement of a battery of cells.

A froth flotation unit or cell embodying the principle of my invention includes a tank 10, a pump 11 and conduit connections 12, 13, whereby pulp is conducted from the tank to a header 14.

2

A motor 15 or other source of power is provided for driving the pump.

I preferably employ a tank having a conical wall which merges into pipe 12 connected to the lower portion of the tank and to the intake side of a pump. While the upper portion of the tank may be variously shaped, a circular flotation area has advantages which will appear in more detail hereinafter.

10 The pulverized ore, which may or may not have been previously treated with oil or other agent, is mixed with water and any desired flotation agent to form a pulp in the usual manner. The pulp is contained in tank 10 and the froth is produced by circulating the pulp through the pump 11, conduit 13 and header 14 and by directing it against the pulp in tank 10.

The header is disposed above the pulp level so that it will discharge through the air. As shown in Fig. 1, the header is provided with a plurality of orifices in the form of spray nozzles 16 whereby the pulp is projected from the header in a number of streams. The streams are projected at a relatively high velocity and in their travel from the header to the surface of the pulp in the tank, air is entrained and froth is produced.

The size of the header and the number and size of the spray nozzles are dependent upon the amount of aeration desired. Different ores and 30 different frothing agents require different degrees of aeration and the amount of aeration may be varied by the use of different numbers of spray nozzles, or by increasing or decreasing the velocity of the spray streams. If desired, the sprays 35 may be directed at an angle to each other so as to cause their streams to focus on one point, and whether the sprays are parallel or angular to each other, other instrumentalities such as one or more deflecting surfaces can be used, if desired, to cause greater agitation and consequent aeration.

In order to minimize friction loss because of the header the total discharge area of the several spray nozzles employed should constitute approximately the area of the pump discharge pipe 13. 45 By way of illustration, sixteen 1-inch sprays provide an aggregate discharge equivalent to a 4-inch discharge pipe; nine 1-inch sprays provide an area equivalent to a 3-inch pipe; four 1-inch sprays provide an area equivalent to a 2-inch pipe; four one-half inch sprays provide an area equivalent to a 1-inch pipe, and two one-half inch sprays will provide an area approximately equivalent to a three-quarter inch pipe, but the discharge velocity may be increased for any given 50 size of discharge pipe by providing spray nozzles

having an aggregate area less than that of the discharge pipe.

For a unit having a 4-inch discharge pipe, sixteen 1-inch sprays will produce a desired aeration of a given pulp and if it is desired to increase the amount of entrained air, such result can be attained by changing the header to one having, say, twenty-eight $\frac{3}{4}$ -inch sprays. In general, the larger the number of sprays the greater the aeration. The use of more nozzles for discharging the same quantity of pulp has the effect of increasing friction head due to the increased circumferential surface area of the greater number of nozzles, with the result that greater pressure is maintained in the header and a higher velocity head ensues. A sufficiently high velocity head should be maintained, whatever the number of sprays, in order to obtain a high emission velocity with consequent high entrainment of air. The friction head due to the spray nozzles need not be large because of their short lengths. It is an advantage of the present invention that the static head upon the pump is relatively low since no great lift of pulp is required.

As illustrated in the drawings, the locus of impact of the sprays upon the pulp contained in the tank is localized by a baffle 20 which extends from above the level of the pulp and sufficiently below its surface to avoid agitation of the pulp outside of the zone of impact of the sprays. The exact location of the lower edge of the baffle depends upon the velocity of discharge through the nozzles and somewhat on the quantity of their discharge.

A sleeve is suitable for use as a baffle and this may be supported on brackets such as 21, 22, 23 and 24. Provision may be made to adjust the baffle to change the height of its lower edge.

The froth formed within the baffle passes beneath its lower edge 25 and then immediately rises to the surface of the pulp outside of the baffle and subsequently overflows the tank. The overflowing froth is collected in a launder 27 from whence it is distributed to a filter.

The level of the pulp within the tank is controlled through the medium of a tails gate 28 whose height is adjustable by the removal or placement of individual weir boards, Figs. 2 and 3. The height of the tails gate determines the depth of the froth above the level of the pulp.

The tails gate 28 is supported outside the tank and within a chamber 29 which has communication with the interior of the tank through an opening 30. A tails discharge conduit or chute 31 has connection with chamber 29 on the discharge side of the weir. Passageway 30 is sufficiently below the surface of the pulp in tank 10 to prevent the entry of froth and its discharge through the tails discharge conduit.

To the extent the invention has been described, the configuration of the upper surface of the tank is immaterial, but there is advantage in making the upper portion of the tank cylindrical about a vertical axis. Such an arrangement enables the employment of a froth skimmer which can travel in a circular path over the area of the pulp protected from agitation. This area surrounds baffle 20 and extends to the edge of the tank. Because of the symmetrical form of the cell, all portions of the froth travel the same distance from the baffle to the outer edge of the tank.

The skimmer comprises a plurality of blades 32 which are suspended from a mounting 33 in the form of a ring. This ring is supported on an annular bearing 34 which is carried by the upper ends of brackets 21, 22, 23 and 24. The blades are

preferably curved and disposed in such a manner as to sweep over the quiet area outside of baffle 20 and direct the froth to the edge of the tank and into launder 27. Mounting 33 carries a gear ring 35 which is engaged by pinion 36. Pinion 36 is driven from a motor 37 which is supported on brackets such as 38, 39.

The present invention provides a positive circulation of the material not held in the froth. All of such material must go either over the tails gate or to the cone at the bottom of the tank. If it goes over the tails gate it may be caught in succeeding cells and offered to the froth in them. If it settles it will be taken into the pump and again offered to the froth through the discharge header. This allows each particle of ore the maximum opportunity of being placed where it belongs, either in the concentrate or in the tailings. A further advantage of the apparatus lies in its ability to float large particles because the mixture of air and pulp is so thorough and also because of the method of circulation.

In Fig. 5 I have illustrated a modified form of cell. In this cell the baffle design is such as to squeeze the froth toward the overflow lip in order to take the greatest advantage of the movement of the froth itself. The tank is similar to that previously described, except that a tapering wall 40 is placed about the baffle sleeve 41 in such a manner as to provide a surface which meets the lower end of the sleeve and is inclined radially outward in the fashion of a cone. An empty space exists between the sleeve 41 and the deflecting wall 40. The inclination of wall 40 is such as to direct the rising froth radially outward from the baffle as it rises to the surface of the pulp. The rising direction of flow is such as to cause the froth to flow towards the lip 42 of the tank and discharge into launder 43. For many operations this construction enables the omission of the use of a wiper for directing the flow of froth over the lip. However, if desired, a wiper may be employed and a mounting for the same is illustrated in Fig. 5. This wiper includes a ring carrying a ring gear 45 and a plurality of blades 46. The wiper is driven in a circular path by a motor 47.

The froth flotation apparatus of the present invention is particularly well suited for use in a battery having a number of cells connected in series because it is possible efficiently to operate these cells from the same floor level regardless of number.

In Fig. 6 I have illustrated a system or battery of cells arranged serially for the recovery of a final concentrate. The feed of pulp to the system is to rougher cell R1 and the pulp may be introduced either directly into the tank of that cell or into the intake side of its pump 52. The tailings from the individual cells are introduced into the next succeeding cell as, for example, the tailings from cell C2 are directed to the intake side of pump 53 of the cell C1, the tailings from cell C1 are introduced into cell R1 through the intake side of pump 52, the tailings from cell R1 are introduced into cell R2 through its pump 54, etc. etc.

The concentrates from the rougher cells R1, R2, R3 and R4 are delivered to the first cleaner cell C1 through a conduit 55 which has connection with the respective launders of the rougher cells and the intake side of pump 53.

The final concentrates are removed from the system through conduit 56 which is the discharge conduit of the second cleaner cell C2. The final tailings are removed from rougher cell R4

through conduit 57. The flow of tailings is in one direction, while the flow of concentrates is in the opposite direction. With all of the cells at one level, it is indifferent whether the pumps under the several cells are set on one floor level or at different levels, because in either arrangement the static heads on all of the pumps remain substantially the same.

What is claimed is:

1. An ore concentrator of the class described, comprising a tank for containing ore pulp and providing a settling space having a discharge outlet; means for recirculating pulp under pressure from and to said tank, said means comprising a pump having its suction side connected to said discharge outlet, spray discharge nozzles directing their discharge against the pulp contained in said tank, said spray nozzles being elevated sufficiently above the level of the pulp to discharge through the open air and aerate the pulp after it leaves said nozzles, and means connecting the discharge side of said pump with said nozzles and providing with said pump a closed conduit from the settling space of said tank to the discharge orifices of said nozzles whereby settling pulp is circulated and forcibly discharged from said nozzles; a baffle in said tank and surrounding the area of impact of the discharge from said nozzles into the pulp in said tank, said baffle being clear of said nozzles and extending to such a height above the level of pulp in said tank as to prevent froth from overflowing its upper edge and extending sufficiently below the level of pulp to confine the area of agitation produced by discharge from said nozzles and to protect from agitation the body of pulp and rising froth outside of the locus of impact of the discharge of said nozzles into the pulp in said tank; a tailsgate having an opening thereto from the side of said tank and providing a weir whereby the level of the pulp in said tank is located intermediate the upper and lower ends of said baffle, and a launder for receiving froth from the tank after it has risen through the pulp outside of said baffle.

2. An ore concentrator of the class described, comprising a tank for containing ore pulp and providing a settling space centrally thereof with a discharge outlet at its lower portion; means for circulating pulp from said settling space and for aerating the circulated pulp by projecting it through the air and into the pulp in said tank, said means including a pump having its suction side connected to said discharge outlet, spray discharge nozzles mounted centrally of said tank and above the pulp level of said tank and directing their discharge through the air and against the pulp contained in said tank, and means connecting the discharge side of said pump with said nozzles and providing a closed conduit from said pump to the discharge orifices of said nozzles whereby a relatively high emission velocity is attainable from said nozzles; a tubular baffle in said tank and surrounding the area of impact of the discharge from said nozzles into the pulp in said tank, said baffle being clear of said nozzles and extending to such a height above the level of pulp in said tank as to prevent froth from overflowing the upper edge of the baffle and extending sufficiently below the level of pulp to confine the area of agitation of said pulp from the

body of pulp surrounding the baffle and to permit the passage of froth beneath its lower edge outwardly of said baffle; a tailsgate having an opening thereto from the side of said tank, and a launder for receiving froth from the tank after it has risen through the pulp surrounding said baffle, said launder being substantially concentric with said baffle for providing uniform distances for all particles of froth to travel from said baffle to the launder.

3. An ore concentrator of the class described, comprising a tank for containing ore pulp, said tank having downwardly converging side walls and providing a settling space with a discharge outlet at its lower portion; means connected with said outlet whereby pulp is recirculated and aerated, said means including a pump having its suction side connected to said discharge outlet, spray discharge nozzles mounted centrally of said tank and above the pulp level of said tank and directing their discharge through the air and against the pulp contained in said tank, and conduit means connecting the discharge side of said pump with said nozzles; a tubular baffle located centrally in said tank and surrounding the area of impact of the discharge from said nozzles into the pulp in said tank, said baffle being clear of said nozzles and extending sufficiently high above the level of pulp in said tank to prevent froth from overflowing its upper edge and extending sufficiently below the level of pulp to segregate a relatively quiet body of pulp outside of said baffle to which froth passes from under the lower edge of said baffle and rises therethrough, a tailsgate having an opening thereto from the side of said tank and providing a weir whereby the level of the pulp in said tank is located intermediate the upper and lower ends of said baffle; a launder surrounding the upper edge of said tank for receiving froth after it has risen through the pulp outside of said tubular baffle, and a tapering wall adjacent the exterior of said baffle flaring upwardly and outwardly for directing the froth rising in the relatively quiet body of pulp outside of said baffle towards the side walls of said tank and launder.
